UNITED STATES PATENT OFFICE.

CHARLES R. SHORT, OF DETROIT, MICHIGAN, ASSIGNOR TO GENERAL MOTORS CORPORATION, OF DETROIT, MICHIGAN, A CORPORATION OF DELAWARE.

HYDROCARBON-MOTOR.

1,377,369.

Specification of Letters Patent. Patented May 10, 1921.

Application filed December 10, 1917. Serial No. 206,442.

To all whom it may concern:

Be it known that I, CHARLES R. SHORT, a subject of the King of Great Britain, and resident of Detroit, Wayne county, State of 5 Michigan, have invented certain new and useful Improvements in Hydrocarbon-Motors, of which the following is a specification.

The invention relates to improvements in hydrocarbon motors, and more particularly 10 to fuel feeding devices therefor.

One of the objects of the invention is to devise a fuel feeding device for hydrocarbon motors which will permit the use of the heavier hydrocarbons.

15 Another object of the invention is to devise a fuel feeding device for hydrocarbon motors which will properly supply a combustible gas in adequate proportions to the volumetric dimensions of the motor.

20 Another object of the invention is to devise a fuel feeding device for hydrocarbon motors which will be maintained at an efficient working temperature, irrespective of climatic conditions.

25 Another object of this invention is to devise a fuel feeding device for hydrocarbon motors which will be economic and efficient under varying load or speed conditions of the motor.

30 Another object of the invention is to devise a fuel feeding device for hydrocarbon motors which will be readily assembled, disassembled or cleaned.

Another object of the invention is to devise 35 a fuel feeding device for hydrocarbon motors which will be of simple and durable construction, and comprising few parts.

Another object of the invention is to devise 40 a fuel feeding device for hydrocarbon motors which will be automatically controlled with reference to fuel and temperature.

Another object of the invention is to devise 45 a fuel feeding device for hydrocarbon motors which will promptly respond for starting purposes.

These and other objects will more clearly appear from the following descriptions taken in connection with the accompanying 50 drawings, which form a part of this specification and in which:

Figure 1 is a side elevation of a hydrocarbon motor showing the fuel feeding device attached thereto.

Fig. 2 is an enlarged vertical sectional view of the fuel feeding device.

Fig. 3 is an enlarged sectional view of a thermostat and its mounting for controlling the temperature of the fuel feeding device.

Like numerals of reference indicate corresponding parts in the several figures.

Referring to the drawings—10 is a hydrocarbon motor of any desired type having the intake ports 11 and the exhaust ports 12, shown in dotted lines, said ports being controlled by suitable valves 13, shown as of the overhead type.

The intake ports 11 and exhaust ports 12 are provided with manifolds 14 and 15 respectively, said manifolds being shown in 70 the drawings as integral, though it must be understood that any desired form or arrangement of manifolds may be used, and the construction thereof is not an essential part of the invention. The intake manifold 14 has a downwardly turned section 16, enlarged toward its lower end to form a mixing chamber 17, and provided with the customary throttle valve 18.

The mixing chamber 17 of the intake manifold is further enlarged at 19 to form a valve chamber, and has the heating chamber 20 arranged therebeneath and preferably formed of a casting 21, substantially rectangular in shape and provided with the 80 openings 22 and 23 at the top thereof and the openings 24 and 25 at the bottom thereof, said casting being secured to the enlarged portion 19 of the intake manifold forming the valve chamber, as by the bolts 26 inserted through portions of the valve chamber wall and threaded into correspondingly threaded orifices in the lugs 27 on the top of the heating chamber, whereby auxiliary or secondary air inlet ports 28, through 85 which air may flow from the external atmosphere into the intake manifold, are provided at intervals around the lower end of the valve chamber.

The opening 22 of the heating chamber 100 is comparatively small and provided about the top thereof with a circumferential flange 29, forming a cup, and having the upper periphery thereof shaped to a valve seat.

A valve 30 is seated upon the upper periphery of the cup 29 and extends to the inner periphery of the valve chamber 19, whereby the secondary port openings 28 are 105

- normally closed, said valve having an upwardly extending cylindrical portion 31 adapted to telescope into the mixing chamber, and being provided with spider arms 32 supporting a central boss 33 in which the upper end of a metering pin 34 is secured and which metering pin extends downwardly therefrom, for the purpose as hereinafter fully described.
- 10 The opening 24 of the heating chamber has a fuel supply chamber 35 connected therewith, said supply chamber comprising a central bushing 36 having the upper end thereof threaded into the correspondingly threaded opening 24, and having the flange 37 extending laterally therefrom immediately below the heating chamber and forming the cover for the shell 38 of the fuel chamber, said shell being secured in place as 15 by a funnel piece 39, threaded onto the correspondingly threaded lower end of the bushing 36 and abutting the bottom of the shell 38, whereby the same is firmly pressed against the flange 37. The bushing 36 of 20 the fuel chamber is provided with the orifice 40 therethrough, said orifice being enlarged toward the lower end thereof as at 41, whereby the nozzle 42 may be supported therein as by the laterally extending section 25 43, formed integral with a side wall of the enlarged orifice 41 in the bushing member. The nozzle 42 is provided with a tip 44 extending upwardly and concentrically into the orifice 40 of the bushing member 36.
- 30 Extending between the orifice 40 of the bushing member and the opening 22 in the top of the heating chamber is a straight tube or conduit 45 forming a direct duct along which air and atomized liquid fuel may 35 flow to the mixing chamber 17; the open lower end of the funnel 39 and the passage 41 providing a primary air inlet passage or port extending past the nozzle tip 44 and into the lower end of the conduit 45, whereby 40 by a rich preliminary mixture of air and fuel will be formed, to which mixture additional air will be supplied through the auxiliary air inlet ports 28 above referred to. The tube 45, toward the upper end thereof, 45 is swaged into the top of the opening 22 of the heating chamber, and extends upwardly in a flare about the central boss 33 of the valve 30.
- The lower end of the tube 45 is fitted into 50 the orifice 40 of the bushing member 36 of the fuel chamber and has the insulating washer 47 surrounding the same, whereby the tube at the lower end thereof is electrically insulated for the purpose as herein- 55 after more fully explained.
- The tube 45 has a spider 46 arranged therein adjacent its upper end and through which the metering pin 34, attached to the valve as hereinbefore described, extends 60 downwardly with the pointed lower end

thereof entering the nozzle tip 44, and thus when the valve 30 is raised from its seat by the suction created in the motor intake manifold to admit air through the port openings 28 to the mixing chamber, the pin 34 70 will also be raised to withdraw the pointed lower end thereof part way from the nozzle and permit a proper flow of liquid fuel from the fuel chamber.

The fuel chamber may be supplied with 75 fuel by any of the well known means, although preferably by the valve mechanism shown in the drawings.

The fuel feeding valve mechanism, as shown, is arranged in the laterally extending 80 portion 48 of the fuel chamber, said extension 48 having the threaded orifice 49 in the top thereof and the threaded orifice 50 in the bottom thereof. The opening 50 is fitted with the correspondingly threaded 85 bushing 51 having the needle valve orifice 52 therethrough enlarged at its lower end and threaded as at 53, said lower end being fitted with the plug member 54 having the tubular stem 55 threaded into the correspondingly 90 threaded orifice 53 of the bushing 51, the adjoining surfaces of the bushing 51 and plug member 54 being ground to properly clamp the fuel feeding piece 56 at the respective ends of the T to complete liquid-tight joints. 95

The tubular portion 55 of the plug member has the lateral orifices 57 therethrough, and further is surrounded by the mesh 58, forming a tubular screen whereby a liquid hydrocarbon may be fed through the branch 100 59 of the T piece and will be strained through the tubular sieve to the center of the T section, and thus find its way to the needle valve orifice of the plug member 51.

The threaded orifice 49 of the fuel chamber extension 48 is fitted with a bushing 60 having the needle valve 61 vertically arranged therein with the lower end thereof seating in the orifice 52.

The needle valve 61 is actuated by the 110 pivoted arm 62 and float 63, as customary in carburetor construction, the float being so arranged in the fuel chamber that the proper level of fuel will be maintained therein in accordance with the height of the nozzle tip 44.

The opening 23 of the heating chamber 20 is connected in any suitable manner with the exhaust of the motor, preferably as shown in the drawings, by being attached, as by 120 bolts 64, directly to the manifold outlet, whereby all of the exhaust gases may be passed through the heating chamber if required, and the heating effect of said gases on the tube 45 is controlled by directing 125 their course through the chamber, which has a damper 65 arranged therein for this purpose and whereby varying portions of the exhaust gas entering said chamber may be caused to flow past the said tube.

The damper 65 is fixedly mounted on a shaft 66 extending through the chamber walls, whereby the damper may be swung to one side of the chamber, as shown in Fig. 2 of the drawings, to direct the gases entering the same about the tube 45, the inner periphery of the chamber being spirally ribbed, as at 67, to aid in directing the flow of gases in an eddy about the tube 45 before they are permitted to pass out of the opening 25, which may be connected, as by bolts 68 with an exhaust pipe. When the damper 65 is swung to a vertical position, as shown in dotted lines in Fig. 2, the exhaust gases entering the heating chamber will find a clear passage therethrough to the outlet opening 25.

The shaft of the damper 65 may be connected by suitable levers 68 and 69 whereby the damper may be manually operated, though it is preferable to have said damper connected, as by the lever 70 and link rod 71, to one end of a rocker arm 72, and having the other end thereof connected, as at 73, to the lower end of the thermostat 74 contained within the casing 75, forming a part of the intake manifold immediately above the mixing chamber. It will thus be understood that the thermostat may be set to operate the damper and so direct the gases through the heating chamber, and that the tube 45 will be maintained at any desired temperature.

The air which enters the funnel member 39 will pass the nozzle tip 44 at a comparatively high velocity and carry particles of the hydrocarbon fuel from the nozzle on through the tube 45, wherein a very rich gas is thus formed and heated to a degree of permanency. This rich gas mixture has a direct and uninterrupted passage through the tube or duct 45 to the mixing chamber, where additional air is permitted to enter as required through the ports 28. This air, though comparatively cool, will readily mix with the rich gas emanating from the tube or duct and complete a combustible mixture at a comparatively low temperature, whereby the motor cylinders will be properly filled in accordance with their volumetric dimensions. At any time the motor speed is suddenly reduced, the valve 30 will lower a corresponding degree, and coincidentally the metering pin will reduce the nozzle opening, thereby preventing any excess hydrocarbon entering the heated tube to generate gas with a smoking effect.

For starting the motor during comparatively cold climatic conditions, it may be preferable to electrically heat the tube 45, and this may be readily accomplished by forming the same of a suitable resistance metal and connecting it with a source of electric current, as at 76, the lower end of said tube being insulated as hereinbefore ex-

plained, whereby the current will flow upwardly through the tube, where it may be grounded or carried through the heater casting to an electric terminal 77.

Although I have described and will claim the preferred embodiment of my invention, it will be obvious to those skilled in the art that many modifications and changes may be made without departing from the scope of the invention.

Having thus described my invention, what I claim and desire to secure by Letters Patent is:

1. In a device of the class described, a heating chamber having an inlet and an outlet opening; a conduit extending through said heating chamber; an adjustable damper located within said heating chamber and adapted to cause varying portions of a heating medium entering said chamber through said inlet opening to flow past said conduit; means for supplying atomized liquid fuel to one end of said conduit; a mixing chamber at the other end of and into which said conduit discharges; an air inlet port leading into said mixing chamber; and a valve for controlling said air inlet port.

2. In a device of the class described, a heating chamber having an inlet and an outlet opening; a conduit extending through said chamber; an adjustable damper located within said heating chamber and adapted to cause varying portions of a heating medium entering said chamber through said inlet opening to flow past said conduit; means for supplying atomized liquid fuel to one end of said conduit; a mixing chamber at the other end of and into which said conduit discharges; an air inlet port leading into said mixing chamber from the external atmosphere; and a suction operated valve for controlling said air inlet port.

3. In a device of the class described, a heating chamber having an inlet and an outlet opening; a conduit extending through said heating chamber; an adjustable damper located within said heating chamber and adapted to cause varying portions of exhaust gases from an engine entering said chamber through said inlet opening to flow past said conduit; means for supplying atomized liquid fuel to the lower end of said conduit; a mixing chamber at the upper end of and into which said conduit discharges; a valve seat surrounding the upper end of said conduit; an auxiliary air inlet port extending past said valve seat and discharging into said mixing chamber; and a suction operated valve coöperating with said valve seat to control the flow of air into said mixing chamber.

4. In a device of the class described, a heating chamber having an inlet and an outlet opening; a conduit extending through said heating chamber; an adjustable damper

- located within said heating chamber and adapted to cause varying portions of exhaust gases from an engine entering said chamber through said inlet opening to flow past said conduit; thermostatic and manually operable means both operatively connected with said damper for operating the same; and means for supplying atomized liquid fuel to said conduit.
- 10 5. In a device of the class described, a heating chamber having an inlet and an outlet opening; a conduit extending through said heating chamber; an adjustable damper located within said heating chamber and adapted to cause varying portions of exhaust gases from an engine entering said chamber through said inlet opening to flow past said conduit; thermostatic and manually operable means both operatively connected with said damper for operating the same; means for supplying atomized liquid fuel to one end of said conduit; a mixing chamber at the other end thereof and into which said conduit discharges; an air inlet port leading into said mixing chamber; and a suction operated valve for controlling said air inlet port.
- 15 6. In a device of the class described, a heating chamber having an inlet and an outlet opening through which exhaust gases may flow into and from the same; a conduit extending through said heating chamber; a thermostatically controlled damper located within said heating chamber and adapted to cause varying portions of the exhaust gases aforesaid to flow past said conduit; a nozzle located adjacent the inlet end of said conduit; and a primary air inlet port extending past said nozzle and whereby a preliminary mixture of air and liquid fuel is formed; a mixing chamber located adjacent the outlet end of and into which said conduit discharges; and means for admitting additional air to said mixing chamber.
- 20 7. In a device of the class described, a heating chamber having an inlet and an outlet opening through which exhaust gases may flow into and from the same; a vertically arranged straight conduit extending through said heating chamber; a thermostatically controlled damper located within said heating chamber and adapted to cause varying portions of the exhaust gases aforesaid to flow past said conduit; a nozzle located adjacent the lower end of said conduit; a primary air inlet port extending past said nozzle and whereby a preliminary mixture of air and liquid fuel is formed; a mixing chamber located adjacent the upper end of and into which said conduit discharges; a valve seat surrounding the upper end of said conduit; a secondary air inlet passage extending past said valve seat and into said mixing chamber; a suction operated valve adapted to control the flow

of air through said passage; and a metering pin carried by said valve and the lower end of which extends into said nozzle.

8. The combination with a hydrocarbon motor having intake and exhaust manifolds, of a fuel supply device having a secondary air intake communicating with said intake manifold, and a primary air inlet port, a jacketed conduit extending from said primary port to said intake manifold, means for supplying a hydrocarbon to said conduit, and means for electrically heating said conduit.

9. A device of the class described comprising a mixing chamber, means for supplying air to said mixing chamber, a jacketed vaporizing conduit communicating with said chamber, means for supplying air to said conduit, means for feeding a hydrocarbon to said conduit, and electric means for heating said conduit.

10. In a device of the class described, a heating chamber having inlet and outlet openings through which exhaust gases may flow into and from the same; an adjustable damper located within said heating chamber and adapted to cause varying portions of exhaust gases entering said chamber through said inlet opening to flow past said conduit; a vaporizing conduit extending through said heating chamber and adapted to be heated by the exhaust gases flowing therethrough; means for supplying atomized liquid fuel to the interior of said conduit; means for electrically insulating one end of said conduit; and means for causing a current of electricity to flow from the insulated end of said conduit through the same and through the wall of said chamber to thereby electrically heat said conduit.

11. A device of the class described comprising a mixing chamber having air inlet port openings, a valve controlling said port openings, a fuel supply chamber beneath said mixing chamber, a conduit connecting said fuel supply chamber with said mixing chamber and having means for supplying fuel thereto from said fuel chamber, a heating chamber arranged about said conduit between said mixing chamber and said fuel supply chamber and having inlet and outlet openings therein and a spirally arranged baffle flange about the interior thereof for directing the course of gases about said conduit, means for supplying heat to said heat chamber inlet opening, a damper arranged in said heat chamber and adjustable to direct the heat passing therethrough about said conduit or toward said outlet opening, and thermostatically operated means governed by the temperature of the gases passing through said mixing chamber for controlling the position of said damper.

12. In a device of the class described comprising a mixing chamber having air

inlet port openings, a valve controlling said port openings, and a fuel supply chamber operatively connected therewith, of a plug member having a tubular portion threaded 5 into an opening in said fuel supply chamber, and a T-shaped fuel connection member surrounding said tubular portion of said plug member and having the head section clamped endwise between the plug end of 10 said plug member and said chamber to form liquid-tight joints.

13. In a device of the class described comprising a mixing chamber and a fuel supply chamber operatively connected there- 15 with, said fuel supply chamber having a lateral extension forming a valve chamber, of a valve bushing fitting the opening in said valve chamber and having the outer face thereof ground to a valve seat, and a thread- 20 ed central orifice reduced to a needle valve opening at the inner end of said bushing, a plug member having the inner face of the plug end ground to a valve seat, and a tubular extension threaded into the central orifice 25 in said valve bushing, said tubular portion having lateral orifices therethrough, a T-shaped member having the head extremities ground to valve faces and clamped between said valve bushing and the end of 30 said plug member about the tubular portion thereof, and a cylindrically shaped screen.

contained within said T member about the tubular portion of said plug member.

14. A device of the class described comprising a mixing chamber having air inlet 35 port openings, a valve controlling said port openings, a heating chamber beneath said mixing chamber and having a metallic wall, means for supplying a heating fluid to said chamber to heat the same, a conduit commu- 40 nicating with said mixing chamber and extending through said heating chamber and formed of a high electrical resistance metal having one end thereof insulated and the other end thereof electrically connected with 45 the wall of said heating chamber, means for supplying a liquid hydrocarbon to the interior of said conduit, and means for conducting an electric current to the insulated end of said conduit and to the wall of said heat- 50 ing chamber.

15. The combination with a hydrocarbon motor, intake and exhaust passages therefor, an enlargement in said exhaust passages, a conduit associated with said enlargement for 55 conducting an explosive mixture to said intake passage, and means for causing a portion or all of the exhaust gases to make a circuitous path within said exhaust passage, to heat the mixture in said conduit. 60

In testimony whereof I affix my signature.
CHARLES R. SHORT.
